KNIFE HANDLE OR THE LIKE

Leonard Garth Huxtable, New York, N. Y., assignor to Millers Falls Company, Greenfield, Mass., a corporation of Massachusetts

Application April 21, 1955, Serial No. 35,620

Term of patent 14 years

(Cl. D22—3)

FIG. 1.

FIG. 2.

FIG. 4.

FIG. 3.

Fig. 1 is a top plan view showing my new design for a knife handle or the like;

Fig. 2 is a side elevational view thereof; and

Figs. 3, 4 and 5 are views on lines 3—3, 4—4, and 5—5, respectively, of Fig. 1.

I claim:

The ornamental design for a knife handle or the like, as shown.
